UNITED STATES PATENT OFFICE.

CARL J. DUNZWEILER, OF CLEVELAND, OHIO, ASSIGNOR TO WILLARD STORAGE BATTERY COMPANY, OF CLEVELAND, OHIO, A CORPORATION OF WEST VIRGINIA.

DESIGN FOR A STORAGE-BATTERY CONTAINER.

Application filed July 2, 1924. Serial No. 10,036. Term of patent 7 years.

To all whom it may concern:

Be it known that I, CARL J. DUNZWEILER, a citizen of the United States, residing at Cleveland, in the county of Cuyahoga and State of Ohio, have invented a new, original, and ornamental Design for a Storage-Battery Container, of which the following is a specification, reference being had to the

accompanying drawing, forming a part thereof.

The single figure of the drawing is a perspective view of the container.

I claim:

The ornamental design for a storage battery container substantially as shown.

CARL J. DUNZWEILER.
